DENTAL CABINET

Jack H. Levey, 1642 San Ysidro Drive,
Beverly Hills, Calif. 90210

Filed Apr. 10, 1969, Ser. No. 16,678

Term of patent 14 years

Int. Cl. D24—02; D6—01

U.S. Cl. D24—1

Fig. 1.

Fig. 2.

Fig. 3.

FIG. 1 is a front perspective view of a dental cabinet embodying my new design;

FIG. 2 is a top plan view of the same;

FIG. 3 is an end elevational view of the same, both ends being identical.

The undisclosed rear portions are plain and unornamented.

I claim:

The ornamental design for a dental cabinet, substantially as shown and described.
